UNITED STATES PATENT OFFICE.

VASILIE VLADUTZ, OF MUNHALL, PENNSYLVANIA.

STREET-CAR FENDER.

No. 839,793.

Specification of Letters Patent.

Patented Dec. 25, 1906.

Application filed May 11, 1906. Serial No. 316,242.

To all whom it may concern:

Be it known that I, VASILIE VLADUTZ, a subject of the Emperor of Austria-Hungary, residing at Munhall, in the county of Allegheny and State of Pennsylvania, have invented certain new and useful Improvements in Street-Car Fenders, of which the following is a specification, reference being had therein to the accompanying drawings.

10 This invention relates to certain new and useful improvements in car-fenders; and the invention has for its primary object to provide novel means in connection with a car for gripping and holding an object should 15 said object contact with said means, such as would occur should a person be accidentally "run down" by a car. To this end I have devised a series of spring-arms which are carried by the front of the car and two rake-like 20 frames carried beneath said car, the latter being operated should the former fail to operate or accomplish their purpose.

In connection with the above mechanism I use certain novel features of construction 25 which, together with said mechanism, will be presently described in detail and then specifically claimed.

The present invention is an improvement upon the car-fender as set forth in my Patent 30 No. 806,604, granted me December 5, 1905, wherein I described a fender of a more complicated construction than my present fender. Consequently simplicity of construction is the principal object of this invention.

35 Referring to the drawings forming a part of this specification, Figure 1 is a plan of a portion of my improved fender. Fig. 2 is a side elevation of the same. Fig. 3 is a detail sectional view of one of the spring-arms. 40 Fig. 4 is a fragmentary perspective view of the same, and Fig. 5 is a perspective view of a locking-bar. Fig. 6 is a perspective view of a part of a car in an inverted position, showing my improved fender attached thereto.

45 To put my invention into practice, I hinge to the front part 1 of a car two plates 2 and 3, said plates being arranged one above the other and supported by detachable hangers 4, which permit of said plates being removed 50 from said car. Each plate carries a pair of oppositely-disposed arc-shaped resilient arms 5 and 6, said arms being disposed to lie so as to present a configuration of a semicircle. The arms 5 and 6 are fixed at their inner ends 55 to the plates 2 and 3 by a bolt and by straps 8. (See Fig. 3.)

The arms 5 and 6 of the plates 2 and 3 have their outer ends held open or spread by contact-rods 9, each rod consisting of a plurality of links 10, which are preferably secured at their meeting ends by a pivotal or knuckle joint 11. The ends of the rods 9 are adapted to impinge against the ends of the arms 5 and 6 and retain said arms in an open operative position. In order that 65 said arms can be opened or moved to the open or spread position, (shown in Fig. 1,) I provide the plates 2 and 3 with bearings 12 12, in which are journaled shafts 14 14. Wound upon said shafts are chains 15 15, 70 these chains being connected to the arms 5 and 6 of the plate. When said arms are to be opened and after said arms are held by the rods 9, the chains are detached from 75 said arms. The shafts 14 14 have rectangular ends 16 16, upon which cranks are placed to rotate the shafts 14 14, and to retain them in a fixed position ratchet-wheels 17 17 and pawls 18 18 are employed.

The plates 2 and 3 intermediate their ends 80 are provided with depending brackets 19 19, and pivotally mounted upon each bracket is a pair of resilient arms 20 20 and 21 21, similar in construction to the arms 5 and 6 previously described. Instead of holding these 85 arms open or spread at their outer ends by rods 9 I provide each pair of arms with rearwardly-extending members 22 22, and engaging said members are locking-bars 23 23, which serve as detents for the arms 20 20 and 90 21 21. The locking-bars 23 23 are formed intermediate their ends with projections 24, a convenient manner of forming which is by simply twisting the bar to form an eyelet, as shown in Fig. 5, and these locking-bars are 95 released to allow the resilient arms 20 21 to close by engagement with the projections 24 of the rear ends of headed plungers 25, slidably mounted in the brackets underneath the 100 arms and extending forwardly in front of the arms.

The bottom of the car is provided with depending side brackets 26 26 and 27 27, and pivotally mounted in said brackets are spring-pressed rake-like frames 28 and 29, 105 each frame comprising a plurality of curved prongs 30. The pivoted ends of said frames at the one side of the car are provided with toothed wheels 31 31 and crank-arms 32 32. Engaging said crank-arms is a two-part 110 jointed rod 33, which normally maintains the frames in the elevated position shown in Fig.

2. To release said frames, I provide the car with depending trip-levers 34, which actuate a lug 35 to impinge against the rod 33 and permit frames 28 and 29 closing to scoop 5 or pick up a person or object beneath said car. To lock said frames in a fixed position, pawls 36 36, carried by the side of the car, are thrown into engagement with the toothed wheels 31 31.
10. In operation should an object strike the headed plungers 25 25 the locking-bars 23 23 will release the arms 20 20 and 21 21, and should the obstacle be a person said arms will tightly grip the body and prevent the 15 same from falling beneath the car. Should the object fail to strike the plungers 25 25, the object will strike the rods 9 9 at a point between the arms 5 5 and 6 6, forcing said rods rearwardly and releasing said arms, 20 which, owing to their resiliency or spring, close or move toward each other at their outer ends, so as to firmly grip the object and hold same. Since the arms 5 5 are independent of the arms 6 6, either pair of arms may be 25 actuated without disturbing the other of said arms. Should the obstacle be in such a position as to lie out of the path of both sets of arms described, as the car progresses the obstacle will be struck by the depending trip- 30 lever 34, thereby moving the lug 35 and releasing the two-part rod 33 from locking engagement with the ends of the crank-arms 32 32, permitting the spring-pressed frames 28 and 29 to close upon the object and prevent the same from being dragged under the 35 car. After each operation the arms 9 and 33 must of course be replaced to again hold the parts ready for operation.
- What I claim, and desire to secure by Letters Patent, is—
1. In a car-fender, the combination with a car, of plates detachably supported by the front part of said car, resilient arc-shaped arms connected at their inner ends to said
- plates, jointed rods retaining said arms in a 45 semicircular configuration, depending brackets carried by said plates, arms mounted upon said brackets and adapted to embrace an obstacle, plungers slidably mounted beneath said brackets, means to hold said arms 50 in an extended position, means actuated by said plungers to release said arms, rake-shaped frames pivotally mounted beneath said car and adapted when released to embrace an obstacle, means to hold said frames 55 in a retracted position and means actuated by an obstacle to release said frames, substantially as described.
2. In a car-fender, the combination with a car, of plates detachably supported by the 60 front part of said car, resilient arc-shaped arms mounted upon said plates, jointed rods retaining said arms in a semicircular configuration, depending brackets carried by said plates, arms mounted upon said brackets and 65 adapted to embrace an obstacle, plungers slidably mounted beneath said brackets, means to hold said arms in an extended position, means actuated by said plungers to release said arms, substantially as described. 70
3. In a car-fender, the combination with a car, of plates hinged to the front of said car, hangers pivoted to said plates and to the car, resilient arc-shaped arms carried by the said plates, means to temporarily retain said 75 arms in a semicircular configuration to be released by an obstacle, rake-shaped frames carried by the bottom of said car and adapted to embrace an obstacle, means to temporarily hold said arms in a semicircular configuration to be released by an obstacle, substantially as described. 80

In testimony whereof I affix my signature in the presence of two witnesses,

VASILIE VLADUTZ.
